His Atty.

UNITED STATES PATENT OFFICE.

DENNIS PARKS, OF ST. LOUIS, MISSOURI.

LIFT-CUTTING MAUL.

1,228,961.

Specification of Letters Patent. Patented June 5, 1917.

Application filed January 7, 1916. Serial No. 70,749.

To all whom it may concern:

Be it known that I, DENNIS PARKS, a citizen of the United States, residing in the city of St. Louis and State of Missouri, have 5 invented new and useful Improvements in Lift-Cutting Mauls, of which the following is a specification.

This invention relates to certain new and useful improvements in a device for use in 10 straight-edging scrap leather and cutting it into a die in matched relation to form pieced lifts, and has for its general object to enable such operations to be performed with facility and rapidity, and with the exercise of 15 the minimum of muscular exertion by the operator.

As practised prior to my invention, a 20 relatively heavy maul was used for straight-edging the leather, and for cutting it into the die, and this maul was raised by one hand of the operator and brought down with some degree of force on the piece of leather held by his other hand over the straight-edging blade, and then over the die, and 25 these operations were repeated by a single operator perhaps several thousand times in the course of a day's work. Such operations were necessarily very fatiguing, and only an operator possessing more than the average 30 strength and endurance could perform such work continuously during the entire day, the average operator finding it necessary to rest his arm at more or less frequent intervals. As compensation for this character 35 of work is usually based on the number of lifts cut during the course of the day, the pay of the operator was curtailed by reason of such periods of inaction, and the output of the factory in this regard proportionately 40 reduced.

According to my invention I mount a maul, much heavier than that ordinarily employed for the operations indicated, on the lower end of a relatively long coil spring 45 which is suspended from a suitable support above the head of the operator. The weight of the maul and the strength of the spring are so proportioned to each other that the weight of the maul will be overcome by the 50 tension of the spring when the bottom of the maul is slightly below the top of the die or straight-edging blade. In practice I provide that the maul shall be in balanced relation when it is at rest on the table on which 55 the die and straight-edge are mounted. This manner of mounting the maul, as will be

apparent, will permit the operator to raise it with the expenditure of scarcely an appreciable amount of power, and will also permit of his bringing the maul down upon the die or straight-edge with the requisite degree of force with the exercise of the like minimum amount of power, the inertia of the maul, when started on its downward course, owing to its considerable weight, being nearly sufficient to complete the stroke with the proper degree of force without the expenditure of power by the operator.

As shown by the accompanying drawing, it is the practice to place the straight-edging 70 blade immediately behind the die, and even with a spring-balanced maul, with the spring attached to the top of the maul, the operation would involve considerable strain on the wrist of the operator in moving the maul 75 to a position over the straight-edging blade and in overcoming the tension of the spring to bring the bottom of the maul to a position parallel with the top of the blade. To overcome this objection I secure the lower end 80 of the supporting spring toward the lower end of the maul, or at what may be termed its center of gravity, and weight the upper end of the maul above the handle, or part grasped by the operator, so that the maul 85 may be overbalanced with the expenditure of but slight power.

The invention is illustrated in the accompanying drawing, in which—

Figure 1 is a view partly in side elevation 90 and partly in section showing a maul mounted for operation according to my invention, in connection with a straight edging blade and a die secured in position on a table;

Fig. 2 is a vertical sectional view of the 95 maul and showing in elevation the lower portion of the spring supporting the same; and

Fig. 3 is a bottom plan view of the handle 100 portion of the maul.

Referring now to the drawing, the numeral 1 indicates a table upon which is mounted a straight-edging blade 2, and a die 3 in the usual manner. Mounted on the top of this table and toward the rear side 105 thereof is a standard 4 which is provided with a flanged base 5 by means of which it may be secured to the table by suitable bolts or screws 6. The upper portion of the standard 4 is curved inwardly, or toward 110 the operator, as indicated at 7, and its outer end is apertured at 8 to support a suitable

flexible hanger 9. I provide resilient means including a cable for supporting the maul. For this purpose, secured at its upper end in the hanger is a relatively long cable in the form of a coil spring 10, to the lower end of which is secured the maul, indicated generally by the numeral 11. This maul comprises a handle portion 12, an enlarged bottom portion 13 which is provided on its under side with a socket 14, and an upper weighted portion 15, the parts described presenting in their entirety somewhat the shape of an ordinary dumb-bell. The upper wall of the socket 14 is provided with a transverse groove 16, and a conical opening 17 extends through the part of the maul described from its upper end into the socket 14, the opening 17 tapering inwardly from its upper to its lower end. The lower portion of spring 10 is attached to the maul by a joint which permits the maul to move relatively to the cable or spring. For this purpose the lower end portion of the spring 10 passes through this opening 17, and at its lower end is secured centrally of a rod 18 which is seated in the groove 16. A circular wooden block 19 is secured in the socket 14 in the usual manner, and serves to prevent the rod 18 from leaving the groove 16. The upper portion of the maul, that is, the handle portion 12, bottom portion 13, and upper weighted portion 15, is preferably cast as an integral structure from iron, and, when the block 19 is secured in position in the socket 14, the maul as a whole is of considerably greater weight than that usually employed in the ordinary hand operation.

Evidently each time the maul is raised to strike, the spring assists the muscular effort of the person operating the maul. The weight of the maul is sufficient to overcome the force of the spring and normally hold the maul in a depressed position.

The tapered opening permits of the distortion of the spring 10 in moving the maul from the die 3 to a position over the straight-edging blade 2, as shown by dotted lines in Fig. 1, with the minimum of friction and wear caused by the contact of the spring with the side walls of the opening 17.

From an inspection of Fig. 2 it will be seen that the maul is partially supported from the spring in such manner that it can be readily overbalanced in manipulating it, and that this will greatly relieve the strain incident to the constant moving of the maul from a position over the die to a position over the straight-edging blade, which nec-

essarily involves the exertion of some force to distort the spring 10; and moreover that such distortion of the spring is minimized by providing the tapering opening 17, which will permit a wide latitude of movement of the maul from a position over the die without bringing the spring into contact with the walls of said opening.

The spring is of such strength that the weight of the maul will extend it sufficiently to hold the maul substantially at the level at which the maul is reciprocated, that is to say, the handle 12 of the maul is normally held within the zone of movement of the maul when in operation.

The manner of using the maul in straight-edging leather and cutting the lifts into the die has been referred to generally above, and such general operation being well known a further description thereof would seem to be unnecessary.

I claim:

1. A device of the character described comprising a maul having a substantially vertically elongated handle for raising the maul and striking downwardly in a substantially vertical plane, and a spring-pulled pendent supporting member attached to said maul substantially at the center of gravity thereof.

2. A device of the character described comprising a maul and a pendent spring connected at its lower end to said maul at approximately the center of gravity thereof.

3. A device of the character described comprising a maul provided with a downwardly-tapering opening, and a pendent spring extending into said opening and connected at its lower end to said maul at approximately the center of gravity thereof.

4. A device of the character described comprising a maul having a handle-portion and being weighted above and below said handle portion, and a pendent spring connected at its lower end to said maul at approximately the center of gravity thereof.

5. A device of the character described comprising a maul having a tubular handle, and resilient means including a cable suspended from above, and freely movable laterally below, the lower portion of said cable passing into said tubular handle and having a joint connection with said maul permitting a movement of said maul with respect to said cable about said joint.

In testimony whereof, I have hereunto set my hand.

DENNIS PARKS.
